[57] CLAIM

The ornamental design for a surgical stapling instrument, substantially as shown and described.

DESCRIPTION

FIG. 1 is a top plan view of a surgical stapling instrument showing our new design;
FIG. 2 is a side elevation thereof;
FIG. 3 is a fragmentary perspective view of the front portion of the instrument; and
FIG. 4 is a fragmentary perspective view of the rear portion of the instrument.

FIG. 1

FIG. 2

FIG. 3

FIG. 4
